(57) **CLAIM**

The ornamental design for a “clutch” as shown and described.

DESCRIPTION

FIG. 1 is a bottom, rear perspective view of a clutch;

FIG. 2 is a top left perspective view thereof;

FIG. 3 is a bottom view thereof;

FIG. 4 is a top view thereof;

FIG. 5 is front view thereof;

FIG. 6 is left side view thereof;

FIG. 7 is a right side view thereof;

FIG. 8 is a rear view thereof;

FIG. 9 is a perspective view showing the clutch in an open position; and,

FIG. 10 is a perspective view with a pill container shown removed from a pouch of the clutch.

The long broken lines show parts of the design and short broken lines show environmental structure which form no part of the claimed design.
